FIG. 2.

FIG. 1.

INVENTOR

Harry D. Weed

BY

John H. Willard

ATTORNEY

UNITED STATES PATENT OFFICE.

HARRY D. WEED, OF SYRACUSE, NEW YORK, ASSIGNOR TO AMERICAN CHAIN COMPANY, INC., A CORPORATION OF NEW YORK.

SNUBBER.

Application filed September 24, 1924. Serial No. 730,507.

To all whom it may concern:

Be it known that I, HARRY D. WEED, a citizen of the United States, residing at Syracuse, in the county of Onondaga, State 5 of New York, United States of America, have invented certain new and useful Improvements in Snubbers, of which the following, taken in connection with the accompanying drawing, is a specification.

10 This invention relates to devices commonly known as snubbers, employed for modifying excessive vertical oscillations of spring-supported vehicle bodies, such as are caused by irregularities in the road surface.

15 The object of the invention is to construct a device of the strap-and-drum type for this purpose, characterized by the provision of means to vary the degree of resistance to recoil of the vehicle springs as the recoil 20 movement progresses, the resisting force, however, remaining practically uniform.

This object is preferably accomplished by providing the drum with a flexible friction-band or element mounted rotatably on the 25 periphery of the drum, and having a radial enlargement or extension which intervenes between the periphery of the flexible friction-element and the conventional strap, cable, or other flexible draft-element when- 30 the latter is wound thereon, the extension acting automatically to vary the moment of rotation of the friction-element about the drum. This peripheral enlargement is desirably formed as a separate part of cres- 35 cent shape secured firmly upon the friction element, so that as the latter is rotated the flexible element is tangent successively to peripheral portions of the crescent differing progressively as to radial extent in suitable 40 proportion to the progress of the recoil movement.

Referring to the drawings:—

Figure 1 is an elevation in section on the line 1—1 of Figure 2.

45 Figure 2 is a side elevation.

In my preferred embodiment, the resistance to recoil of the vehicle springs, (which are not shown herein, not forming any part of this invention,) is created mainly by friction, this friction arising out of the rotation of a suitable split friction-band 1, consisting for example of ordinary brake-lining surrounding the periphery of a brake-drum indicated as a whole by the numeral 2. This 50 drum consists of a suitable back plate 3

from which projects a central hollow hub 4 and also the annular flange or projection 5, the periphery of which serves as one of the brake surfaces. In order to stiffen the 55 brake-lining it is attached to a split, flexible, steel band 6 which preferably tends normally to cause the brake-lining to be slightly sprung away from close contact with the 60 brake-surface on the drum, and therefore permits the lining to rotate freely, when 65 properly actuated and not constrained from such rotation.

The actuating means for causing rotation may consist of a cable 7 wound about the 70 outer periphery of the steel band through a sufficient arc to permit the maximum extent of vertical oscillation likely to take place under given conditions of service. The cable may be attached to the friction 75 lining by any suitable means, such as the button or stud 8. The drum may be attached to the body or frame of the vehicle by means of the bolt 9 in the usual manner and it is thereby not only rigidly secured against dislocation but is also fixed against 80 rotation. The cable may be attached to any suitable part of the vehicle which is spring-connected with that part of the frame carrying the drum and is therefore subject to oscillation relatively thereto, as for example 85 the axle.

Means consisting of a helical spring 10 may be used for maintaining suitable yielding tension against the draft of the cable, one end of the spring being anchored to the 90 back plate 3 by hooking it through the aperture 11. The free end of the spring is secured to an arm 12 rotatably mounted on a journal 13 projecting from the hub 4. The 95 spring, as may be observed from the drawings, is designed to exert its force in a direction to rotate the band against the tension of the cable 7, i. e., in counter-clockwise direction as indicated by the arrow D in Figure 2.

The arm 12 is provided with a turned over portion 14 which abuts against the turned-over end 26 of the steel band 6, at the end of the brake lining, and exerts its 105 force in the direction of the arrow D in Figure 2; i. e., in such a direction as to keep the cable 7 under constant tension. The free end 15 of the spring 10 may be conveniently anchored by hooking it through an 110 aperture 18 in the arm 14.

On the steel band 6 is a radial extension or enlargement 16 which may take any desired form for accomplishing the purposes of the invention. In the drawings I have shown this extension of crescent shape as viewed from the side, being formed as a separate member secured to the band 1 by rivets 17.

When the radius of rotation of the brake band coincides with that radius which passes through the point of tangency of the cable with the thickest portion of this crescent-shaped extension, the moment of rotation is obviously at the maximum and the resistance to rotation of the friction-band on the drum is at a minimum. These quantities vary from point to point on the extension 16 as the band revolves, and it is obvious that by suitably proportioning the dimensions of the extension, any desired variation in the moment of rotation may be secured.

Ordinarily, it is desired that the resistance to rotation of the brake-band shall be at a minimum when the body and axle of the vehicle are relatively at rest, whether or not the vehicle as a whole be in motion. It may be assumed for purposes of illustration and explanation that the parts as shown in Figure 2 are in the position which they would occupy with the vehicle and axle relatively at rest. The radius of revolution at that junction is, therefore, as indicated by OA and the resistance to rotation of the brake-band is then at its minimum. This arrangement permits the conventional vehicle springs to function with comparatively reduced resistance until the oscillations exceed a predetermined amplitude. If, however, a compression of the vehicle springs takes place the radius of revolution decreases as the extension 16 is revolved upwardly by the action of the coil-spring 10 working through arm 12 and band 6, and it may be assumed that the radius OB becomes the radius of revolution at the extremity of a compression. The resistance to turning is, therefore, a maximum at the commencement of a recoil movement. This resistance decreases until the radius OA again intersects the point of tangency of the cable, and thereafter, as the recoil movement continues, the resistance again increases, reaching a maximum when, for instance, the radius OC intersects the point of tangency of the cable. As stated above, the character of the changes which take place in the amount of resistance is a matter of choice to be determined in view of the purposes to be accomplished in the particular case. I have described and shown an apparatus in which the changes are characterized in a way that I have found suitable under many conditions. I am aware, however, that the opinions of those familiar with the art

vary on this question, some being of the opinion that the resistance should be at a minimum at the commencement of a recoil movement and should increase to a maximum as the movement approaches its extreme. On the other hand, it is the opinion of others that the resistance should be a maximum at the commencement of a recoil movement and gradually become reduced as the movement approaches its extreme. Any of these requirements, however, can, as is obvious, be satisfied by suitable modification of the shape of the extension, which is well within the skill of the ordinary mechanic, or in the case of an extension of given dimensions by initially setting the drum at the particular angular position which will produce the desired result.

Having thus described my invention, I claim:

1. In a snubber, a brake-drum, adapted to be connected non-rotatively with one of two spring-connected members of a vehicle; a rotatable friction element surrounding the periphery of said drum; a draft-element co-acting peripherally with said friction element to cause rotation thereof and adapted to be connected with the other of said two spring-connected members of the vehicle for actuation thereby; and means to vary the moment of rotation of said friction element about said drum, said means comprising a peripheral extension upon said friction element at a portion thereof co-operating with said draft element.

2. In a snubber, a brake-drum, adapted to be connected non-rotatively with one of two spring-connected members of a vehicle; a flexible, rotatable, friction-element surrounding the periphery of said drum; a flexible draft-element connected with said friction-element and coiled about the same and adapted to be connected with the other of said two spring-connected members of the vehicle; and means to vary the moment of rotation of said friction-element about said drum, said means comprising a peripheral extension upon said friction-band, at a portion thereof co-operating with said draft-element.

3. In a snubber, a brake-drum and means to connect said drum non-rotatively with one of two spring-connected members of a vehicle; a flexible, rotatable friction-band surrounding the periphery of said drum; a flexible draft-element coiled about, and connected with, said friction-element, and adapted to be connected with the other of said two spring-connected members of the vehicle; and means to vary the moment of rotation of said friction-element about said drum, said means comprising a peripheral enlargement upon said band having portions of different radial extent, to be engaged progressively by said flexible draft-element.

4. In a snubber, a brake-drum, a flexible brake-band, and a flexible draft-element, superimposed co-axially in the order named, and said brake-members being arranged for retarded relative rotation by said flexible draft-element, during unwinding thereof upon development of tension on said snubber in use; means tending continuously to wind said draft-element on said brake-members when the tension thereon is relaxed; and means to vary automatically the moment of rotation of said flexible brake-band about said brake-drum, said means intervening between adjacent co-operating portions of said flexible draft-element and said brake-band and comprising a radial extension or enlargement of said flexible brake-band.
5. In a snubber, a brake-drum, a flexible brake-band, and a flexible draft-element, superimposed co-axially in the order named, and said brake-members being arranged for retarded relative rotation by said flexible draft-element, during unwinding thereof upon development of tension on said snubber in use; means tending continuously to wind said draft-element on said brake-members when the tension thereon is relaxed; and means to vary automatically the moment of rotation of said flexible brake-member about said cylindrical member, said means intervening between adjacent co-operating portions of said flexible draft-element and said flexible brake-member and comprising a crescent-shaped radial extension or enlargement upon the periphery of said flexible brake-band.
6. In a snubber, a cylindrical brake-drum, a flexible brake-band, and a flexible draft-element, superimposed co-axially in the order named, and said brake-members being arranged for retarded relative rotation by said flexible draft-element, during unwinding thereof upon development of tension on said snubber in use; means tending continuously to wind said draft-element on said brake-members when the tension thereon is relaxed; and means to vary automatically the moment of rotation of said flexible brake-band about said cylindrical member, said means intervening between adjacent co-operating portions of said flexible draft-element and said flexible brake-band and comprising a radial extension or enlargement of said flexible brake-member, taking the form of a crescent-shaped part formed separately, and secured upon the periphery of said flexible brake-member.
7. In a snubber, a brake-drum, a peripheral brake-band thereon, and a flexible draft-element wound upon said brake-band and connected therewith, said brake members being arranged for relative retarded rotation by said flexible draft element during unwinding thereof upon development of tension on said snubber in use, and a coiled spring tending continuously to wind said draft-element upon said brake-band when said tension is relaxed; said brake-band having a crescent-shaped extension engaged by said draft-element to vary automatically the moment of rotation of said brake-band about said drum.
8. In a snubber, a brake-drum and means to secure said drum non-rotatively in adjusted rotative position upon one of two spring-connected members of a vehicle; a flexible, resilient, split, friction-band surrounding the periphery of said drum and rotatable thereon; a snubbing cable connected with, and coiled about, said friction-band, and adapted to be connected with the other of said two spring-connected members of the vehicle; a coiled spring intermediate said brake-drum and friction-band and tending normally to cause rotation of said band relatively to said drum in a direction suitable to wind said cable upon said friction band; and means to vary the moment of rotation of said friction-element about said drum, said means comprising a peripheral extension upon said friction-band, in position to be acted upon by said cable, the position of said extension relatively to the point of tangency between said cable and band being controllable by adjustment of said drum rotatively upon its support.
9. In a snubber, a brake-drum having an axial bolt to connect said drum non-rotatively with one of two spring-connected members of a vehicle; a flexible, split, rotatable friction-band surrounding the periphery of said drum; a flexible draft-element connected with said friction-element and coiled about the same and adapted to be connected with the other of said two spring-connected members of the vehicle; a radial arm mounted to rotate about the axis of said drum, and having a portion extending into position to engage one end of said split band, and a spring coiled about said axis and connected with said drum and arm respectively, tending normally when wound up to rotate said arm and band to maintain tension on said cable, and means to vary the moment of rotation of said friction-element about said drum.

In testimony whereof, I have signed this specification.

HARRY D. WEED.
